UNITED STATES PATENT OFFICE.

JOHN ISEMAN, OF ROSSTON, PENNSYLVANIA.

IMPROVEMENT IN JOINERS' SQUARES.

Specification forming part of Letters Patent No. 35,159, dated May 6, 1862.

To all whom it may concern:

Be it known that I, JOHN ISEMAN, of Ross-ton, in the county of Armstrong and State of Pennsylvania, have invented a new and useful Implement or Device for Joiners' Use, and which I term a "Pitch-Square;" and I do hereby declare that the following is a full, clear, and exact description of the same, reference being had to the accompanying drawings, making a part of this specification, in which—

Figure 1 is a side view of my invention; Fig. 2, an edge view of the same; Figs. 3, 4, 5, and 6, side views of the same, showing the adaptability of the implement to various purposes.

Similar letters of reference indicate corresponding parts in the several figures.

This invention consists in inserting in a straight wooden stock or straight-edge a joiner's or carpenter's square in such a manner that the length of rafters for a roof may by a very simple adjustment of the parts of the implement be accurately ascertained, the height of the roof and the length of the space being given, the implement also being capable of being used as a trying-square, T-square, or miter, as hereinafter fully shown and described.

To enable those skilled in the art to fully understand and construct my invention, I will proceed to describe it.

A represents a joiner's or carpenter's square constructed of metal, as usual, but having both blades *a b* slotted longitudinally nearly their whole length, as shown at *c c* in Figs. 1, 3, and 4. This square is graduated at its outer part into inches and sixteenths, and at its inner parts into inches and twelfths, the latter graduation being the most convenient for measuring the length of rafters, as the twelfths correspond to foot-measurements.

The square A is fitted in a wooden stock or straight-edge, B, which is formed of two longitudinal parts, *d d*, connected by dowel or steady pins *e e*, which keep said parts in a proper relative position with each other. (See Fig. 2.) The square A is secured on the stock or straight-edge B by means of bolts C C, which pass through oblong longitudinal slots *f f* in the stock, and through the slots *c c* in the square, the bolts C C being provided with thumb-nuts D, which admit of the bolts being readily loosened when desired in order to adjust the square in the stock.

The edge of the stock B which is opposite the angle of the square is graduated into inches, as shown in Fig. 2, the inches from 0 to 6, inclusive, being subdivided into twelfths, and at each side of those points subdivided into sixteenths.

The implement is used as follows: Suppose, for instance, that it is required to ascertain the length of the rafters of a roof the span of which is thirty-two (32) feet and the perpendicular height sixteen (16) feet. The square A is so set in the stock or straight-edge B that its shortest blade, *a*, will be in contact with the fourth division on said blade—that is, supposing a quarter inch is to represent a foot. The blade *a* therefore represents the perpendicular height of the roof. The blade *b* is also set so that the fourth division on it will be in contact with the 0 or zero-mark on stock B. This blade *b*, therefore, will represent one-half the span of the roof, sixteen quarter inches representing sixteen feet, thirty-two feet being the span. It will thus be seen that the portion of the stock B between the two points which are in junction with the square will represent the rafter, the quarter inches between the two points aforesaid being counted, and representing feet—the length of the rafter.

The outer gradations on the stock B, the sixteenth divisions of the inches, conform to the graduations on the outer part of the square, and the central twelfth divisions from 0 to 6 conform to the inner graduations on the square, either graduation being used, as desired.

The implement may be advantageously used for laying out the treads of a staircase, as shown in Fig. 4. It also may be used as a miter, as shown in Fig. 3, for a T-square, as shown in Fig. 5, or for a trying-square, as shown in Fig. 6, the square A admitting of being readily adjusted relatively with the stock B to effect these ends. A spirit-level may be inserted in the stock B, if desired.

Having thus described my invention, what I claim as new, and desire to secure by Letters Patent, is—

The combination of the square A and straight-edge B, arranged and connected together as and for the purpose herein set forth.

JOHN ISEMAN.
